(57) CLAIM

The ornamental design for a sofa cover, as shown and described.

DESCRIPTION

FIG. 1 is a front perspective view of a sofa cover, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown with the console in an open position; and,

FIG. 9 is a perspective view of the console component of the sofa cover, shown separately to show aspects of the design that are not visible when combined and shown with the console in an open position.
